UNITED STATES PATENT OFFICE.

ALERI A. RODGERS, OF ESTLIN, SASKATCHEWAN, CANADA.

DISK-SCRAPER.

1,306,629.

Specification of Letters Patent. Patented June 10, 1919.

Application filed October 16, 1918. Serial No. 258,420.

To all whom it may concern:

Be it known that I, ALERI A. RODGERS, a subject of the King of Great Britain, and a resident of Estlin, Saskatchewan, Dominion 5 of Canada, have invented a new and Improved Disk-Scraper, of which the following is a description.

My invention relates to scrapers comprising a blade and shank adapted to be bolted to the upper end of a supporting standard 10 to the axle of the disk.

The prime object of my invention is to provide a counter-balanced scraper-blade shank so that the weight of the arm will tend 15 to hold the blade to its work against the disk.

More specifically, an object of the invention is to provide a counter-balancing attachment of a form that may be employed 20 in connection with scraper blades and shanks of known form.

Reference is to be had to the accompanying drawings forming a part of this specification, it being understood that the drawings 25 are merely illustrative of practical examples of the invention.

Figure 1 is a perspective view of a disk plow equipped with scrapers embodying my invention in one form;

30 Fig. 2 is a detail perspective view on an enlarged scale, showing one disk and my improved scraper attachment;

Fig. 3 is a perspective view illustrating the preferred form of my attachment.

35 The invention is shown applied to a disk plow of known form including disks A mounted to revolve in the usual manner, there being associated with the disks supporting standards B, the upper ends of 40 which are adapted to receive a pin C held by an eye bolt D, the shank of the usual scraper blade being adapted to be secured to said pin. In the form shown in Fig. 2 the scraper blade 10 has a shank 11 pivotally secured between its ends by a bolt 12 or the like to the pin C or equivalent supporting means, so that the shank is free to rock on 45 said pivot. The end 13 of the arm beyond the pivot 12 is offset laterally to lie at an angle to the blade and to the forward part 50

of the shank, and said arm 13 is counter-balanced preferably by means of a slidable box weight 14 thereon, adapted to be secured in fixed position by a set screw 15.

With the described arrangement the 55 weighted arm 13 maintains the blade 10 to its work against the disk A. In the form shown in Fig. 3 the blade 10^a is substantially of known form having a short shank 11^a secured by a pivot 12^a. A separate 60 weight arm is employed which is provided by means of a lever 13^a pivoted between its ends on the pivot 12^a to present a longer and a shorter arm, the longer arm having a weight 14^a and set screw 15^a corresponding 65 with the similar features in Figs. 1 and 2. The shorter arm 13^b of the lever is provided with a hook 16 upturned to engage the shank 11^a of the blade and thereby throw said blade upwardly to maintain the blade in working 70 position against the disk under the action of the weight. The weighted lever 13^a with its hook 16 is adapted to be employed with 75 scraper blades and shanks of known form to counter-balance the latter. The pivot pin 75 or bolt 12^c is provided in the downturned end of standard B' corresponding in general with the standard B.

I would state in conclusion that while the 80 illustrated example constitutes a practical embodiment of my invention, I do not limit myself strictly to the mechanical details herein illustrated, since manifestly the same can be considerably varied without departure from the spirit of the invention, as defined in the appended claims.

Having thus described my invention, I claim as new, and desire to secure by Letters Patent:

1. A scraper attachment for plows, including a scraper blade having a shank adapted to be pivotally mounted on a plow to position said blade for scraping, a counter-balance element, means to pivotally mount said element and shank, and means on said element to engage said shank and subject the scraper to the weight of said element to hold the scraper blade to its work. 90

2. A scraper attachment for plow disks or the like, including a scraper blade, a shank 95

100

thereon adapted to be pivotally mounted adjacent to a plow disk to position the blade for scraping, a lever pivoted between its ends, and a hook on one arm of the lever engaging the said shank, the other arm of the lever being counter-balanced.

3. An attachment for disk scrapers, said attachment comprising a lever adapted to

be pivotally secured on a support, adjacent to a scraper shank, and means on said lever 10 to engage the scraper blade shank, said lever being counter-balanced to exert a leverage on the shank of the scraper blade for maintaining the latter in scraping position.

ALERI A. RODGERS.
